UNITED STATES PATENT OFFICE.

GEORGE MOORE, OF JOPLIN, MISSOURI.

DEWATERING AND REPLACEMENT APPARATUS.

1,231,411.

Specification of Letters Patent. Patented June 26, 1917.

Application filed December 11, 1914. Serial No. 876,742.

To all whom it may concern:

Be it known that I, GEORGE MOORE, a citizen of the United States, residing at Joplin, in the county of Jasper and State of Missouri, have invented certain new and useful Improvements in Dewatering and Replacement Apparatus; and I do hereby declare the following to be a full, clear, and exact description of the invention, such as will enable others skilled in the art to which it appertains to make and use the same.

This invention relates to improvements in de-watering and replacement apparatus of the type especially adapted for effective use in the replacing of liquid possessing dissolved contents in solids by liquid possessing less dissolved contents or no dissolved contents.

The object in view is increasing the speed of replacement both by increasing the speed of settling of suspended solids into coagulated settled masses and by moving the solids against a counter current of replacing liquid.

With this and further objects in view as will in part hereinafter be stated and in part become apparent, the invention comprises certain novel constructions, combinations and arrangements of parts as will subsequently more fully appear and thereafter be particularly pointed out in the claims.

10 In the accompanying drawing:

Figure 1 is a sectional elevation of an apparatus embodying the features of the present invention, the settler being seen in end view and a portion of the tank in section.

20 Fig. 2 is a vertical section through the part seen in Fig. 1, the section being taken approximately on the plane of the axes of the settler, and parts of the settler being seen in elevation.

25 Fig. 3 is a detail fragmentary view showing the parts on an exaggerated scale.

Fig. 4 is a view similar to Fig. 1 of a further embodiment.

30 Fig. 5 is a sectional elevation on a greatly reduced scale of a further embodiment.

Fig. 6 is an enlarged, fragmentary plan showing a slightly modified form of settler plate.

Referring to the drawing by numerals, 1
35 indicates a tank having a hopper bottom 2, provided with the discharge at its lower end controlled by valve 3. At the upper portion of tank 1 a launder 4 or other appropriate conduit for the discharge of solutions is provided. A pulp supply pipe 5 extends into

tank 1 and is adapted to receive pulp from any appropriate source.

Fixed to each end of tank 1 is a bracket 6 each of which is in the form of a U-shaped bar providing a vertical channel terminating at its lower end in a bearing in which is mounted the respective journal 7 of the rotary settling apparatus, consisting essentially of a plurality of juxtaposed superimposed plates 8, 8. While plates 8, 8 may be 60 of fabric or other suitable material, they are preferably of relatively thin metal, as for instance, sheet steel of the thickness of approximately one-thousandth of an inch, and each is spaced above the next lower plate a 65 distance appropriate for insuring rapid settling of suspended solids, the distance being preferably relatively very small, in practice usually being about one quarter of an inch. The plates 8 by preference are of different 70 widths, varying from the narrowest at the top and bottom to the widest at the center, so that the complete assemblage of plates which will, for convenience, be referred to as the settler, forms approximately a cylinder. Each plate is formed with apertures 33 for enabling free access and circulation of solids of pulp to and about inner portions of the plates. As seen in Fig. 5 in addition to the apertures 33, each plate may be formed 75 of strips 8' having longitudinal spaces therebetween, or the spaces may be employed in lieu of the apertures. The plates are held in their spaced relation by appropriate retaining means, such, for instance, as through 80 bolts 9, 9, retaining the spacers 10, 10 in position between the several plates. Each spacer 10 consists of a strip of wood or other appropriate material extending transversely 85 of the plates 8 and of a length equal to the width of the particular plates engaged, the ends of each strip being beveled or rounded off so that at one face the strip is the same length as the width of one plate and at the other face, the strip is the same length as the width of the other plate. Extending across each end of the settler is a flat bar or other appropriate journal support 11, having terminal flanges 12 extending over the uppermost and beneath the lowermost plate 9, the flanges being engaged by the respective 90 terminal through bolts 9. Each plate 11 is provided with the outstanding journal 7, which journals are axially aligned on the longitudinal axis of the settler. 95

Fixed to one of the journals 7 is a sleeve carrying crank arm 13 to the outer end of which is pivotally connected a link 14, which extends to and is operatively connected with a chain of power transmission devices 15 for effecting longitudinal reciprocation of the link either at regular intervals or as desired, the settler being thus adapted to be moved angularly through approximately 90° ninety degrees for causing the several plates 8 to be moved from a horizontal to a vertical position and to be returned to the horizontal position.

In operation, tank 1 is filled with pulp through pipe 5 and the supply of pulp is preferably maintained proportional to the withdrawal of solids passed valve 3 and of solution through conduit 4. The solids in suspension, finding their way throughout all portions of the space between plates 8, settle rapidly on the plates. The rate of settling will be greatly augmented over that of settling on widely spaced plates, since the solids have to travel in operation of this structure, a minimum distance to arrive at a lodging point, and any particular lamination of pulp is sufficiently thin to largely avoid interference of the solids in the course of settling by other viscous solids already partly settled. After an appropriate deposit of solids is formed on the several plates 8, the plates are moved from their horizontal position, by actuation of link 14, to the vertical position where the solids drop by gravity, the coagulated settled solids falling from the plates descending through the surrounding fluid far more rapidly than would non-coagulated suspended solids.

This apparatus, while capable of general use, is particularly well adapted for metallurgical and other similar operations wherein it is desirable to cause solids to be alternately placed in suspension and settled to a coagulated state, and for the purposes of the claims of this application, the apparatus, as so employed, is to be considered a preferred embodiment. One specific illustration of this embodiment is indicated in detail in Fig. 4, wherein are seen successive tanks 16, 16, each having a discharge hopper 17, provided with a discharge pipe 18, controlled by valve 19. Each pipe 18, with the exception of that of the last tank of the series, is provided with an air-lift 20 for delivering the solids into a tube 21 discharging into the lower portion of the next rearward tank, which tube 21 is preferably provided with a funnel 22 receiving the discharge from the air-lift. At the rear end of the series, the last tank 16 is provided with a water supply pipe or conduit 23, one of the intermediate tanks is provided with a barren solution supply pipe 24, and preferably next to the first tank of the series is provided with a pulp supply pipe 25, the

first tank of the series being provided with a solution-discharge launder or conduit 26. The barren solution, as is well known in the art, is usually cyanide solution, free from metals, but may be any appropriate solution according to the particular treatment to which the solids are being subjected. The various points of supply and the relative quantities of supplied solutions is such as to insure an advance flow from what I have arbitrarily designated as the last tank of the series toward the first or in a forward direction, until the solution is discharged through launder 26, and to effect this result, each tank is provided with an internal tube 27, opening into the tank near the lower end of the tank and near the upper end opening into the next rearward tank.

In each tank is arranged one or more of the settlers. By preference I have indicated two such settlers at 28, 28, each being constructed and operating the same as the settler above described, the two settlers for each tank being connected by links 29 and 30 and a lever 31 to a reciprocating operating rod 32, the rod 32 being actuated by mechanism not illustrated, and in such timed relation to the operation of the entire device as to effect the best results in the settling and discharge of solids in the several tanks.

It is to be noted that as the solutions move generally in one direction, the solids move generally in the opposite direction, so that the effective results obtainable by the action of a counter current are secured.

The advantage of rigidly connecting the several plates in each settler so that the plates maintain substantially the same spacing at all times, is apparent since, if the plates were free to move toward each other they would interfere with free discharge of settled solids, and might become so positioned as to render the operation of the particular settler ineffective. The spacers 10 are, therefore, used to insure prevention of the plates from being moved to positions restricting the spacing therebetween.

In the operation of the structure seen in Fig. 4, the coagulated settler solids descend rapidly so that but limited opportunity for replacement during descent would be afforded but for the fact that the larger or heavier particles descending from the plates of the upper settler strike upon the edge of the plates of the lower settler and are broken up into smaller portions of solids which descend less rapidly. To secure the full benefit of this phase of the operation of the structure, it is desirable to arrange several of the settlers one above the other and to this end an effective embodiment of the apparatus is seen in Fig. 5, wherein a relatively long, upright tank 1' is provided having the hopper bottom 2' provided with the valved

outlet 3'. At the upper end of the tank, the launder 4' is provided for decanting the more or less clarified solutions. Pulp is supplied to the tank 1' through the supply apparatus 5 5', which delivers the pulp at a point near but not at the upper end of the tank. Barren solution is supplied through pipe 24' to the tank about midway of its length, and wash water is supplied to the tank at the 10 lower portion thereof through pipe 23'. A series of settlers 28', similar in structure, mounting and operation to the settlers 28, are arranged one above the other in tank 1, the operating or rotating apparatus being 15 omitted from the showing.

The operation of the structure seen in Fig. 5 is quite similar to that above set forth, differing only in degree as to the number of plates positioned for being struck by descending masses of solids. In operation, the pulp is supplied through pipe 5 and barren solution and wash water are supplied in quantities sufficient for replacement, the 20 quantities being governed according to the nature of tailings discharged at 3'. The pulp solids are permitted to settle on the plates of settlers 28' until an appropriate sheet or mass of coagulated settled solids is formed on each of the plates, and thereupon, 25 the plates are moved from a horizontal to a vertical position, that is, from a position adapted to sustain settled solids to a position enabling gravity discharge thereof. In this position, the edges of all the plates will 30 be exposed upward, and descending masses of solids will repeatedly contact with the edges of the plates of the successive settlers and thus be interrupted in their descent and sufficiently broken to afford opportunity for 35 effective replacement in the mass of settled solids of the contained solutions by solutions of less dissolved contents or of no dissolved contents. The solution of maximum dissolved contents is drawn off through launder 4' while the moisture discharging with 40 solids drawn off at 3' is free from dissolved contents, or at least as free as can be maintained while effectively working the apparatus.

50 **What I claim is:**

1. In apparatus of the class described, the combination, with a container, of spaced plates movably mounted therein and adapted, while maintained substantially without 55 reduction in the relative spacing, to be

moved from a position for sustaining settled solids of pulp to a position enabling gravity discharge of such solids from the plates.

2. In apparatus of the class described, the combination, with a container, of spaced plates rigidly connected together and movably mounted in the container, and means for moving the plates from a position for sustaining settled solids of pulp to a position enabling gravity discharge of such solids from the plates.

3. In apparatus of the class described, a series of successive containers connected for the flowing of contained liquid from the container at one end of the series toward the container at the other end of the series, plates movably mounted in one of the containers and adapted to be moved substantially without variation in location relative to each other from a position for sustaining solids settled thereon from the contained liquid to a position enabling gravity discharge of such solids from the plates, and means for delivering the discharged solids to a container in the rear relative to the direction of flow of the contained liquid.

4. In an apparatus of the class described, the combination with a container, of a plurality of series of movably mounted plates, one of the series being superimposed with respect to another, and means for moving the several plates from a position for sustaining the settled solids to a position enabling gravity discharge from the plates, a plate of the superimposed series being positioned relative to a plate of the subposed series for causing gravity discharge solids from the superimposed plate to contact with the edge of the subposed plate in the course of descent.

5. In an apparatus of the class described, the combination, with a container, of spaced plates connected to form a relatively rigid body and movably mounted as a body and adapted to be moved from a position for sustaining settled solids of pulp to a position enabling gravity discharge of such solids from the plates.

In testimony whereof I affix my signature in presence of two witnesses.

GEORGE MOORE.
